UNITED STATES PATENT OFFICE

2,547,897

ADJUSTABLE BACK REST FOLDING CHAIR

Brunislaw F. Wozniak, Lynn, Mass.

Application June 4, 1947, Serial No. 752,321

1 Claim. (Cl. 155—161)

1
This invention relates to folding chairs and has particular reference to articles of this class commonly known as lawn chairs.

The invention has for its object to provide an improved folding chair of the type referred to which will be of simple, efficient and comparatively inexpensive construction. Another object of the invention is to provide improved means for maintaining the parts of the chair in their extended and useable relationship. A further object of the invention is to provide simple and inexpensive means for adjusting or varying the angular relationship between the back of the chair and the seat of the latter.

To these ends I have provided an improved chair of the class described which, in the preferred embodiment of the invention, may be constructed as set forth in the following description, the novel features of the invention being particularly pointed out and defined in the claim at the close of the description.

In the accompanying drawings:

Figure 1 is a top plan view of a folding chair constructed in accordance with this invention, said chair being shown in its extended or useable condition.

Figure 2 is a side elevation of the chair shown in Fig. 1.

Figure 3 shows the chair of Figs. 1 and 2 in its folded or collapsed condition.

Figure 4 is a section on line 4—4 of Fig. 2.

The illustrated embodiment of the invention, when adjusted for use, comprises a pair of up-standing relatively parallel and spaced apart front legs 10, 10, made from wood and pivotally connected intermediate their opposite ends as at 11 (Fig. 2) to the front ends of a pair of rearwardly inclined side-bars 12, 12, of wood whose rear end portions provide rear legs to rest upon the ground.

The upper or higher portions of the side-bars 12, 12 constitute parts of a seat which also includes a plurality of transverse seat slats 13 fastened at their opposite ends by screws or otherwise in positions upon the side-bars 12, 12. These seat slats 13, together with a transverse tie-rod 14 (Fig. 2) that is also fixed at its opposite ends to the side-bars 12, serve to connect said side-bars so as to provide a rigid base structure for the chair.

A back rest is provided for the chair comprising a pair of relatively parallel spaced-apart side-bars 15, 15, to which are fastened, by screws or otherwise, the opposite ends of transverse slats 15'. The side-bars 15 are pivotally connected as

at 16, 16 (Figs. 1 and 2) adjacent to their lower ends to the upper ends of wooden brackets 17, 17, fastened by screws or otherwise in position upon the outside of the side-bars 12, 12.

5 The side-bars 15 of the back rest are fitted against the inner sides or faces of the brackets 17 and therefore are disposed in the same vertical fore-and-aft plane with the side-bars 12 of the base structure with the lower extremities of the side-bars 15 in immediate proximity to arcuate surfaces 18 provided upon the side-bars 12 of said base structure, said arcuate surfaces 18 being concentric with the pivots 16. This construction is provided so that when the chair is in condition for use stresses imposed laterally upon the upper portion of the back rest will be opposed by the engagement of the lower ends of the side-bars 15 with said arcuate surfaces, and at the same time angular adjustment of the back rest is provided for.

20 Each side-bar 15 of the back rest is made at its lower end with an inwardly off-set extension 19 which, through engagement with a suitable stop carried by the base structure, limits the rearward swing of its side-bar 15 on its pivot 16. Under one condition of adjustment of the back rest the extensions 19 engage one or more of the transverse slats 13 of the base structure to limit the rearward angular adjustment of said back rest so that it is supported in the position shown by full lines in Fig. 2. Under another condition of adjustment of the chair these extensions of the side-bars of the back rest engage a pair of supplemental stop members 20, 20 (Fig. 4) that are 25 adjustably mounted in position against the under side of one of the slats 13 of the seat. As shown in Figs. 1 and 4 each stop member 20 consists of an oblong block of wood adjustably fastened to its slat 13 by a pair of screws 21 which occupy 30 slots 22 (Fig. 1) formed longitudinally through said block. One of these two stop blocks is disposed adjacent to one of the extensions 19 and the other block is disposed adjacent to the other extension. The two blocks are shown in their retracted inoperative positions but it will be clear 35 that when they are adjusted toward and against the inner sides of the side-bars 12 they will occupy positions in the paths of the extensions 19 and serve to limit the rearward angular adjustment 40 of the back rest so that it is supported by said blocks in the position indicated by dotted lines in Fig. 2.

45 The upper end of each front leg 10 is pivotally connected at 23 to one end of an arm 24 whose 50 opposite end is pivotally connected by a bolt 25

directly to one of the side-bars 15 of the back rest. Thus while the chair is occupied the back rest acts through the arms 24 to maintain the front legs 10 in upstanding operative position, but when the chair is not occupied the parts thereof may be adjusted relatively on the pivots 16, 25, 23 and 11 into the compact assemblage illustrated in Fig. 3 by swinging the back rest forwardly on the pivot 16.

What I claim is:

A folding chair of the character described comprising, when in useable condition, a pair of upstanding front legs; a pair of inclined rear legs pivotally connected adjacent to their forward ends to said front legs intermediate the opposite ends of the latter and provided with a seat for the occupant, each of said inclined rear legs being provided between its front and rear ends with an upwardly extending outwardly off-set bracket; a back rest comprising a pair of side-bars pivotally connected adjacent to their lower ends to said brackets in positions where they are disposed in the same vertical planes with said rear legs with their lower extremities in immediate proximity to arcuate surfaces provided upon said rear legs which are concentric with said pivotal connec-

tions thereby to afford lateral support to the back rest, said side-bars being made at their lower ends with inwardly off-set extensions disposed between said rear legs that are engageable with the under side of said seat to limit the rearward pivotal movement of said back rest relatively to said rear legs, and arms pivotally connected adjacent to their rear ends to said side-bars and also pivotally connected adjacent to their forward ends to the upper end portions of said front legs.

BRUNISLAW F. WOZNIAK.
